HEATING TORCH BURNER

Filed July 10, 1941

UNITED STATES PATENT OFFICE

2,359,251

HEATING TORCH BURNER

Harold G. Seamans, Spring Lake, Mich.

Application July 10, 1941, Serial No. 401,838

1 Claim. (Cl. 158—27.4)

My present invention relates to improvements in heating torch burners, and particularly to heating torch burners employing the flame of a combustible fuel consisting of gas and oxygen for heating, to harden or to anneal ferrous metal bodies; and the objects of improvement are, first, to provide a heating torch burner whereby a combustible fuel composed of natural gas and oxygen can be employed to produce the combustion flame having the intense heat temperature required for heating heavy ferrous metal bodies; second, to provide a heating torch burner that will produce from natural gas and oxygen a combustion flame equally high in heat units as flame produced by like burners employing acetylene gas and oxygen; third, to provide a heating torch burner that is simple to construct; fourth, to provide a heating torch burner that is not liable to disorder; fifth, to provide a heating torch burner that can be readily cleaned internally; sixth, to provide a heating torch burner that will be cheap to produce.

I attain these named objects and such other objects as may appear from a perusal of the following description, when said description is taken in connection with the structure disclosed in the accompanying drawing, in which—

Figure 1 is a side elevation view of my improved heating torch burner, the view showing the slot at one end from which the combustion flame issues, the combustible fuel supply pipe by which the combustible fuel is delivered to the burner and the cooling fluid conductor pipes by which the cooling fluid is delivered to and conducted from the burner.

Figure 2 is an elevation view of my heating torch burner illustrating the end with the combustion flame slot and combustible fuel discharge nozzles therein.

Figure 3 is an elevation view of my heating torch burner illustrating the end thereof with the combustible fuel supply pipe and cooling fluid pipe passages into which is secured their respective pipes.

Figure 4 is a side elevation view of the burner body member, showing the combustion flame slot, one of the combustible fuel longitudinal transfer passages and cooling fluid transversely extending header passage.

Figure 5 is a longitudinal sectional view of my heating torch burner taken on a horizontal plane looking downward from line IV, IV, of Figure 1, the view showing the passages through which the combustible fuel is conducted from the supply

pipe to the nozzles and therethrough to the combustion flame slot.

Figure 6 is a longitudinal sectional view of my heating torch burner taken on a horizontal plane looking downward from line V, V, of Figure 1, the view showing the passages through which the cooling fluid flows in cooling the burner to prevent over heating.

Figure 7 is a cross-sectional view of my heating torch burner taken on a vertical plane extending transversely through the burner on line X, X, of Figure 1, and as when looking in either direction from said line.

Throughout the several views of the drawing, 15 similar numerals designate similar parts or portions of my improved heating torch burner, and referring thereto—

Numeral 1, designates the body portion of my heating torch burner having therein at the back 20 end thereof longitudinally extending combustible fuel supply passage 2 into which extends combustible fuel conductor tube 3, the combustible fuel supply passage 2 being open to transversely extending combustible fuel passage 4 joined at the 25 ends thereof to passages 5 extending longitudinal of the burner body and connected to combustible header passage 6 from which extend a plurality of nozzles 7 of a desired size and at each side of the 30 plurality a nozzle 8 which is slightly larger in cross-sectional area than the nozzles 7. Extending transversely across the burner is combustion flame slot 9 into which the several nozzles discharge the combustible fuel and in which ignition of the combustible fuel takes place. Cover plates 10 35 closing the several passages and the header within the burner body 1, and have at the ends of passage 4, pockets 11 that cause eddy currents within the combustible fuel before it enters the passages 5, and at the ends of the header passage 6, pockets 40 12 by which additional eddy currents are caused within the combustible fuel and by reason of these eddy currents cause a complete mixing of the gas and oxygen beyond the extent they are mixed before delivery to the burner. Pipe 13 having connection with a source of cooling fluid supply, extends into passage 14 through which cooling fluid flows to the transversely extending passage 15 and therefrom to passage 16 and to the pipe 17 whereby the cooling fluid is conducted away from the 45 burner. At each end of the header passage 15 in the cover plates 10, are cushion pockets 18, and from the said header passage 15, at such times as the heating torch burner is used for heating metal bodies that require cooling directly after a portion has been heated, cooling fluid spray nozzles 50 55

may be drilled through the end of the burner body into the cooling fluid passage 15 at numeral 19, the said nozzles being no part of my present invention are not shown.

In the operation of my improved heating torch burner, it is preferably mechanically supported in close relation to the metal body to be heated, and when so supported, a cooling fluid such as water is conducted from a source of supply to the cooling fluid passages within the burner body by the tube 13 as shown in the drawing, and which may have connection with a flexible extension to permit changing position of the burner in relation to the metal body being heated, and from the passages within the burner body the cooling fluid is conducted away from the burner body by tubing such as 17 of the drawing, and when the cooling fluid is in circulation within the said passages the combustible fuel mixture of gas and oxygen is admitted through conductor tube 3 to the transverse passage 4 from passage 2, at which place it flows in two directions to the longitudinal passages 5 and therefrom into the nozzle header passage 6 and therefrom the combustible fuel is discharged through the nozzles comprising a plurality thereof of relatively small nozzles 7 and at each end of the plurality, a nozzle of slightly greater capacity, which is required because the end nozzles of the plurality of closely spacing of the nozzles pick up oxygen from the atmosphere and therefore require a greater amount of gas to produce a like mixture as that of the smaller nozzles, all of which discharge into the combustion flame slot 9 wherein is combined the combustible fuel discharged from all of the nozzles and thereby pro-

ducing a combustion flame of continuous heat the complete length of the flame slot, and uniform heating throughout the width of the combustion flame front.

5 Having described my invention, the rights to which I desire to secure, are disclosed by the claim hereafter enumerated:

In a heating torch burner, the combination of an elongated rectangular body having a transversely disposed combustible fuel passage adjacent one end of the body and having a plurality of nozzles extending therefrom to the end of the body and having a cushion pocket at each of its ends, a passage at each side of the body extending from the said transversely disposed combustible fuel passage substantially parallel with the sides of the body and having a cover plate closing one side of each passage, another combustible fuel passage extending transversely of the body and open to both said combustion fuel passages having the cover plates and having a cushion pocket at each of its ends and extending substantially parallel with one end of the body and having extending therefrom a combustible fuel supply passage with a combustible fuel supply pipe extending therefrom and a cooling fluid circulating passage comprising cooling fluid supply and discharge passages having a portion adjacent the end of the body having the plurality of combustible nozzles and extending transversely of the body in substantial parallel relation to the transversely disposed combustible fuel passage and tubes for conducting cooling fluid to and from the cooling fluid circulating passage substantially as described.

HAROLD G. SEAMANS.
